Inventor:

William V. Kay

United States Patent Office.

WILLIAM V. KAY, OF CHICAGO, ILLINOIS, ASSIGNOR TO S. S. SAR-
GEANT, OF NEWARK, NEW JERSEY.

Letters Patent No. 90,849, dated June 1, 1869.

IMPROVED BUCKLE.

The Schedule referred to in these Letters Patent and making part of the same.

To all whom it may concern:

Be it known that I, WILLIAM V. KAY, of Chicago, in the county of Cook, in the State of Illinois, have invented an Improved Buckle; and I do hereby declare that the following is a full and exact description thereof, reference being had to the accompanying drawings, and to the letters of reference marked thereon, making a part of this specification, in which—

Figure 1 is an elevation of the buckle.

Figure 2, a side view of the same.

Figure 3, a perspective representation of the wedge-tongue.

The object of my invention is to improve the buckle for which Letters Patent were granted to A. H. Cole, October 10, 1865, so as to adapt it to all thicknesses of traces.

A serious objection attending the use of buckles constructed according to said patent is, the liability of the wedge-shaped piece to loose out, and the inoperativeness of the buckle, consequent on such an event; and

Its nature consists in casting the wedge-tongue with lugs, or arms, extending outward far enough to bear against the standards of the main loop, and thus hold the tongue in place, notwithstanding the thickness or worn condition of the trace.

In order to give a correct understanding of my invention, I have marked corresponding parts with similar letters, and will now give a detailed description.

A represents the plate, which is attached to the short tug; C, the loop for back-strap; E, the loop for belly-band; and F Z, the loop for the trace, constructed and arranged, in every respect, similar to Cole's patent, referred to, and are, therefore, not claimed as new.

The wedge G, shown more clearly at fig. 3, is made to operate in the loop F Z, and hold the trace in place, and is similar to the wedge used by Cole, except the hook I, and its lugs J K, which are entirely different in the following respects:

The hook I, at the end of the wedge, is made straight,

and, consequently, has a bearing the entire length of the bar F of the loop, and has the lugs J K cast solid to it, and forming a part of the hook I, for the purpose of providing a support against the standards Z of the loop, and thus preventing the wedge from working out of the same, when a thin trace is used, or an old one becomes worn.

In order to show distinctly the difference between the two inventions, I have drawn a red line, S, on the hook of the wedge, at fig. 3, which shows that Cole makes no provision for keeping the wedge in place, except a hook, having a bearing against only a part of the bar F, in consequence of which the buckle cannot be used for all thicknesses of traces, as is the case with a wedge-tongue, arranged with lugs to bear against the standards Z, as described.

The buckle can be made with my improvement in the same manner, and of the same kind of material as now used for the purpose of manufacturing Cole's buckle, without the improvement, and at the same cost.

When the buckle is to be adjusted for use, the wedge-tongue G should be put through the loop F Z before the trace is, which is easily done by putting one of the lugs through first.

The trace can then be put through and adjusted as desired.

Having thus described my invention, What I claim, and desire to secure by Letters Patent of the United States, is—

The lateral projections J K, arranged upon the inner extremity of the wedge G, and so proportioned to the loop F Z, that whilst they are free to pass therethrough, before the trace is inserted, they prevent its possible loss, after the trace is connected with the tug, substantially as set forth.

WILLIAM V. KAY.
